DEVICE FOR INSERTION IN A CHILD'S BUCKET TO PRODUCE AN ORNAMENTAL SAND HEAP

Albert Harry Barcott, Upshire, Waltham Abbey,
England

Application January 11, 1950, Serial No. 7,146
In Great Britain July 28, 1949

Term of patent 3½ years

(Cl. D34—15)

To all whom it may concern:

Be it known that I, Albert Harry Barcott, a British subject, residing at Warlies Farm Cottage, Long Street, Upshire, Waltham Abbey, Essex, England, have invented a new, original, and ornamental Design for a Device for Insertion in a Child's Bucket to Produce an Ornamental Sand Heap, of which the following is a specification, reference being had to the accompanying drawing, forming part hereof, in which:

Figure 1 is a perspective view of a device for insertion in a child's bucket to produce an ornamental sand heap, showing my new design;

Figure 2 is a top plan view thereof;

Figure 3 is an underneath plan view thereof;

Figure 4 is a side view thereof; and

Figure 5 is a section on the line X—X of Figure 2.

I claim:

The ornamental design for a device for insertion in a child's bucket to produce an ornamental sand heap, as shown.

ALEXANDER HARRY BARCOTT.
